UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,304,689.

Specification of Letters Patent. Patented May 27, 1919.

Original application filed May 22, 1916, Serial No. 99,059. Divided and this application filed November 4, 1918. Serial No. 261,000.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing, being a division of 10 original application filed May 22, 1916, Ser. No. 99,059.

My invention relates to typographical machines such as linotype machines of the general organization represented in Letters Patent of the United States to Ottmar Mergenthaler, No. 436,532, wherein circulating matrices are released from a magazine in the order in which their characters are to appear in print and then assembled in 15 line, the line transferred to the face of a mold, the mold filled with molten metal to form a slug or linotype against the matrices which produce type characters thereon, and the matrices thereafter elevated and re- 20 turned through a distributing mechanism to the magazines from which they started. More particularly, the invention relates to machines of this class in which provision is made for removing the magazines and re- 25 placing the same by another containing a different font of characters, and the invention is directed to certain improvements designed to facilitate the removal and replacement of the magazines, which improvements will be pointed out in the detailed description to follow.

In the accompanying drawings I have shown my invention embodied in a machine of the kind illustrated in my prior 40 Letters Patent No. 1,104,512, but it is equally applicable to machines of other kinds, or to typecasting and typesetting machines, etc., which handle type or dies instead of matrices. In other words, I 45 have shown my invention only in preferred form by way of example, and obviously many changes may be made therein and in its mode of application which will still be comprised within its spirit. Generally 50 speaking, I desire it to be understood that I do not limit myself to any specific form or embodiment except in so far as such limitations are specified in the claims.

Referring to the drawings:

Figure 1 is a side elevation of a portion 55 of a linotype machine having my invention applied thereto;

Fig. 2 is a similar view showing the parts in a different position;

Fig. 3 is a section on the line *a—a* of 60 Fig. 2;

Fig. 4 is a section on the line *b—b* of Fig. 3; and

Fig. 5 is a view similar to Fig. 4 showing the parts in different position.

In the accompanying drawings:

The matrices are stored according to font in the magazines A and B which in the present case are arranged to be shifted upwardly and downwardly so that one or the other may be brought into operative relation to the assembler entrance C and the distributing mechanism D. These magazines are mounted respectively upon the customary base frames A' and B' in such manner that the magazines may be readily removed from the base frames and other magazines substituted therefor containing different fonts of matrices; and the matrices are released from the particular magazine 75 which for the time being is in use, by means of escapement mechanisms E arranged in two banks or series, one bank for each magazine. Each escapement mechanism consists as usual of a rocking lever 80 and a pair of pawls which are projected alternately by the lever into the corresponding magazine channel to control the release of the matrices, the said rocking levers being operated from the keyboard of the 85 machine by actuating reeds G and operating levers H.

In the form of machine shown, the base frames A' and B' carrying the respective magazines may by the operation of a hand 95 lever I be moved upwardly from the position shown in Fig. 1, and then separated from each other as shown in Fig. 2 in order to facilitate the removal of the magazines, and as the mechanism for thus manipulating these parts is foreign to my present invention and is described and claimed in an original application filed by me on the 22nd day of May, 1916, Ser. No. 99,059, of which the present application is a division, a description of such mechanism will be un- 100 105

necessary for an understanding of this invention.

My present invention is concerned with the method of mounting and supporting the escapement mechanisms on the respective base frames, and since both series of escapements are identical in construction and mounting, the present description will be confined to one series only, the one selected being applied to the upper base frame A'. The escapements comprising the rocking levers and pawls above mentioned, are supported in series in a bar or frame K which is pivotally connected to the base frame 10 as at K' so as to allow the escapements to be swung into and out of operative relation to the magazine at will to permit the independent removal or replacement of the magazine. The escapements are held in operative relation to the magazine by a pair of spring actuating latches L which are pivotally connected to the upper ends of laterally swinging arms M pivoted below as at M' to the side members of the escapement frame K. 20 It is merely necessary therefore to disengage the latches from the magazines to permit the downward swinging of the escapements. It will be apparent, however, that when the escapements are moved out of operative relation to the magazines, the contained matrices would be free to pass therefrom unless they were first locked therein. Devices are therefore provided to prevent the disengagement of the latches L until the matrices have been locked in the magazine. 30 In this instance (see particularly Figs. 3, 4 and 5) such devices comprise a plate N mounted to slide backwardly and forwardly in guideways in the upper face 35 of the left side member of the escapement frame, the said plate being provided at its rear end with a locking stud or projection N' adapted to engage in a recess or aperture in the forward face of the adjacent latch carrying arm M. The plate N is formed in its upper side with an inclined slot N² wherein engages the inclined stem portion O of a Z-shaped block O' mounted to slide transversely to the right and left 40 in corresponding guideways in the escapement frame. Due to this interconnection of the parts, the movement of the block O' to the right and left effects a corresponding movement of the plate N forwardly and 45 backwardly respectively, causing the locking stud N' to be engaged with or disengaged from the arm M. A spring P bearing at one end against a fixed portion of the escapement frame and at its opposite 50 end against an upstanding nose Q on the block O' tends to constantly hold the latter to the right and consequently the plate N rearward with its locking stud N' engaged with the recess in the swinging arm 55 M. Disengagement of the locking stud is

effected by the usual matrix locking bar R which is inserted through the edge of the magazine in the customary manner. This bar, as it is pushed home, engages the right end of the sliding block O' and shifts it to the left against the action of its spring, thereby withdrawing the locking stud from the recess in the arm M as shown in Fig. 5. When the matrices are so locked in the magazine, the arms are free to be swung 75 upwardly to disengage the latches L therefrom (see Fig. 3) and the escapement frame may be then swung downwardly to detach the escapements from the magazine as shown by dotted lines in Fig. 2. The magazine may then be removed independently 80 from the machine and when its substitute is put into place, the escapements are swung back into operative relation thereto, and securely engaged therewith. The magazines being separated from each other as shown in Fig. 2 there is ample space between them to permit the downward swinging of the escapements for the upper magazine when the latter is to be removed. 90

It will be understood that while I have shown my invention in connection with a machine employing two magazines movable with their base frames as described, and separable from each other, it will be understood that the invention is not confined to its application to two magazines nor to magazines movable with their base frames, but is applicable as well to machines employing a single magazine as will be appropriate to those skilled in the art. 100

Having thus described my invention, its construction and mode of operation, what I claim and desire to secure by Letters Patent of the United States is as follows: 105

1. In a typographical machine, the combination of a magazine, an escapement supporting frame having sustaining devices to engage the magazine, a locking plate carried by the escapement frame to engage the sustaining devices and prevent their detachment from the magazine, and a matrix retaining device adapted to shift the locking plate to inactive position. 110

2. In a typographical machine, the combination of a magazine, an escapement supporting frame having laterally swinging sustaining devices to engage the magazine, a locking plate carried by the escapement frame to engage the sustaining devices and hold them in operative position, and a matrix retaining device adapted to shift the locking plate to inactive position. 115

3. In a typographical machine, the combination of a magazine, an escapement supporting frame having sustaining devices to engage the magazine, a movable locking plate to hold the sustaining devices in operative position, a movable block connected to the locking plate for shifting it to active 120 position, and a matrix retaining device 125 adapted to shift the movable block to inactive position. 130

- or inactive position, and a matrix retaining device adapted to operate the movable block.
4. In a typographical machine, the combination of a magazine, an escapement supporting frame having sustaining devices to engage the magazine, a movable locking plate to hold the sustaining devices in operative position, a movable block connected to the locking plate for shifting it to active and inactive position, a spring connected to the movable block and tending constantly to hold the locking plate in active position, and a matrix retaining device adapted to engage the movable block and through its connection with the locking plate to shift the latter to inactive position against the action of the spring.
5. In a typographical machine, the combination of a magazine, with an escapement supporting frame provided with the laterally swinging sustaining arms M, the sliding locking plate O' to engage one of the arms and formed with the inclined slot N², and the transverse sliding Z-shaped block O' having its inclined stem portion O slidably engaged in the slot N², together with the matrix retaining bar R adapted to engage and operate the block O'.
6. In a typographical machine, the combination of a magazine, with an escapement supporting frame provided with the laterally swinging sustaining arms M, the sliding locking plate O' to engage one of the arms and formed with the inclined slot N², the transverse sliding Z-shaped block O' having its inclined stem portion O slidably engaged in the slot N², and the spring P tending constantly to move the block O' to the right to hold the locking plate in its active position, together with the matrix retaining bar R adapted to engage the block O' and shift it to the left to withdraw the locking plate.
7. In a typographical machine, the combination of a magazine, an escapement sup-
- porting frame having a pivoted sustaining arm formed in its side face with a recess, a sliding plate carried by the escapement frame and provided with a locking stud to engage in said recess, and a matrix retaining device adapted to shift the plate to disengage the locking stud from the recess of the sustaining arm.
8. In a typographical machine, the combination of a magazine, with an escapement supporting frame provided with the laterally swinging sustaining arm M formed with a recess in its side face and carrying the spring actuated latch L which engages a part of the magazine, the sliding plate N carried by the supporting frame and provided with the locking stud N' to engage in the recess of the sustaining arm, and the matrix locking bar R adapted to shift the plate N to disengage the stud N' from the recess of the sustaining arm.
9. In a typographical machine, the combination of a magazine, a pivoted escapement frame, a sustaining arm pivoted to the escapement frame and carrying a latch to engage the magazine, a sliding plate to engage the sustaining arm and prevent its pivotal movement, and a matrix locking bar adapted by its movement to engage the sliding plate and shift it to unlocking position.
10. In a typographical machine, the combination of a magazine, a pivoted escapement frame, a sustaining arm pivoted to the escapement frame and carrying a latch to engage the magazine, a sliding plate to engage the sustaining arm and prevent its pivotal movement, a spring for holding the plate in its locking position, and a matrix locking bar adapted by its movement to shift the plate to unlocking position against the action of the spring.

In testimony whereof, I have affixed my signature hereto.

DAVID S. KENNEDY.
